United States Patent

Des. 236,760
Patented Sept. 9, 1975

236,760

KEY HOLDER

Robert C. Brown, Sr., P.O. Box 1166,
Vallejo, Calif. 94590

Filed July 16, 1973, Ser. No. 379,301

Term of patent 14 years

Int. Cl. D3—01

U.S. Cl. D87—8

FIG. 1 is a side perspective view of a key holder showing my new design;

FIG. 2 is a side elevational view thereof;

FIG. 3 is an elevational view of the opposite side;

FIG. 4 is a top plan view; and

FIG. 5 is an edge view.

I claim:

The ornamental design for a key holder, as shown in the accompanying drawing.
